UNITED STATES PATENT OFFICE.

HERMAN NORECK, OF NORFOLK, VIRGINIA.

BROILER.

1,057,449.

Specification of Letters Patent.

Patented Apr. 1, 1913.

Application filed March 21, 1911. Serial No. 615,963.

To all whom it may concern:

Be it known that I, HERMAN NORECK, a citizen of the United States of America, and a resident of Norfolk, in the county of Norfolk, State of Virginia, have invented 5 a certain new and useful Broiler, of which the following is a description.

My invention relates to improvements in broilers, in which a double dripping grate 10 operates in conjunction with a multitude of gas jets above the grate, directing the flames downward toward the grate, and a multitude of gas jets underneath directed upward toward the grate; and the objects of my improvement are: 1st, to provide a grate which will broil meat or other foods from below and above at the same time without turning; 2nd, to save time in the operation of broiling; 3rd, to save material, and particularly the grease and juices from the 15 broiling meat; 4th, to simplify the broiler in construction and in operation; 5th, to make a durable and efficient broiler of low cost of construction and simplicity of operation. I attain these objects by the mechanism illustrated in the accompanying drawings, in which—

Figure 1 is a front elevation, partly broken away to show the frame; Fig. 2 is a cross-section of Fig. 1; Fig. 3 is a side elevation of the right-hand side of Fig. 1, showing the gas-pipe connections and stop-cocks; Fig. 4 is a side elevation of the left-hand side of Fig. 1 showing the drip trough; Fig. 5 is a perspective view of the upper member of the grate; Fig. 6 is a perspective view of the lower member of the grate; Fig. 7 is a bottom plan of the lower member of the grate, showing the tying strips; Fig. 8 is an end elevation of the upper member of the grate, showing the tying strip. Fig. 9 is an end elevation of the lower member of the grate, showing the tying strip. Fig. 10 is a modification of the 20 upper member of the grate.

Similar letters refer to similar parts throughout the several views.

A is the body of my improved broiler; B is one of the upper perforated burner pipes, 25 and B' is one of the lower perforated burner pipes; C and C' are the burner cocks; D is the drip trough; E is the inlet gas supply pipe connected with the burner pipes B and B'; F is the receptacle for the grease and juices, and f is a connecting pipe from the 30 trough D to the receptacle F.

G is the upper member of the grate, consisting of a plurality of grate bars g, each convex upward and each separated from its adjacent bar by a narrow longitudinal 60 space g'.

H is the lower member of the grate, comprising a plurality of grate bars h, concave upward, each separated from the adjacent grate bar by a narrow longitudinal space h'. 65

I and I' are tying strips holding the grate bars of G and H in their proper place spaced longitudinally apart as shown at g' and h'.

My improved broiler comprises essentially 70 a double grate, the lower member H of which is formed of a series of grooved bars, h, each bar concave or V-shaped upward, above and near which is a grate G with another series of bars g concave downward, each bar in the upper grate spreading the space h' between two adjacent bars of the lower grate. The upper and lower members of my double grate are 75 spaced apart perhaps for half an inch, and are inclined as a whole endwise a little, and at the lower end of the lower series and underneath it is a transverse trough D inclined transversely for collecting the greases and juices from the broiling meat and discharging and saving the same in a receptacle F. 80

Above the grate is a double walled plate of like area with the grate, the lower side of which contains numerous small perforations 90 acting as gas jets, and into the inclosed space of the double-walled plate a supply of combustible or fuel gas is lead for broiling the meat from above, but I have shown in the drawings the preferable form of 95 burner pipes B, each with perforations directed downward, for gas jets. About the same distance below the grate, say about four inches, a series of gas burner pipes B' are arranged in the same plane with each 100 other, with numerous perforations upward acting as gas jets and adapted to broil the meat at the same time from below.

The operation of my double grate broiler is to place the meat or food to be broiled 105 upon the grate G, turning on and lighting the gas jets above and below. As the broiling proceeds, the upper grate G, the bars g of which are convex upward, directs the exuding juices and grease into the concave 110 bars h of the grate H below without waste, along which by the slope of the grate end-

wise the juices are collected in the trough D, and the broiling is accomplished from above and below without turning, in the time ordinarily required for a single operation, where the meat is broiled from one side only. I may employ this grate most advantageously with fuel gas, but I may also employ it in the ordinary coal-fire grill, where the broiling is accomplished by burning coals below.

Having now described my invention, what I claim as new and desire to secure by Letters Patent is—

In a broiler, a double grate, the lower member of which comprises grooved grate bars concaved upward in combination with

an upper grate, whose bars are convex upward, each arranged over the space between the bars of the lower grate, means for projecting downward from above the grate bars 20 and over their entire area numerous gas flames, and means for projecting upward from below the grate bars and over their entire area numerous gas flames.

In witness whereof, I have hereunto set 25 my hand at the city, county and State of New York, this 13th day of March, 1911.

HERMAN NORECK.

In presence of—
Jos. R. RANAGAN,
FRANK ENTERNIA.
